UNITED STATES PATENT OFFICE.

FRANK A. BUECHNER, OF BATTLE CREEK, MICHIGAN.

FOOTBALL.

Application filed July 11, 1925. Serial No. 42,986.

To all whom it may concern:

Be it known that I, FRANK A. BUECHNER, a citizen of the United States, residing at Battle Creek, in the county of Calhoun and

5 State of Michigan, have invented certain new and useful improvements in Footballs; and I do hereby declare the following to be a full, clear, and exact description of said invention, such as will enable others skilled 10 in the art to which it appertains to make and use the same.

My invention relates to foot balls in which an inflatable bladder or container is provided with an internal extending valve stem 15 formed with an outer end rim adapted to lie between the closing flap of the casing and the casing itself.

A characteristic feature of my invention is the provision of a neck of a valve stem 20 carrying an integrally-formed rim at its end adapted to seat on the lacing flap through which said neck extends, and a base rim to said valve stem to be vulcanized to the bladder.

25 Another object is to construct a valve stem capable of withstanding a maximum of side and torsional strain, yet flexible for the admission of inflating nozzles.

An object of the invention is to so form 30 the valve of an inflatable bladder that it will not be necessary to unlace the casing to either inflate or deflate said bladder.

Another object of the invention is to so 35 form the valve and the closing flap whereby when the neck of the valve is inserted through said flap it will retain the parts in a normal and proper position.

Another object of the invention is to so 40 construct a ball and its valve whereby it will not necessitate the infolding of a valve stem preparatory to closing the casing either by sewing or lacing.

Still another object of my invention is to 45 so form the valve stem of an inflatable ball whereby its more vulnerable portion will be duly and substantially reinforced.

Still another object of the invention is to 50 so construct the neck, or that portion of a valve stem adapted to receive the closing flap, whereby said valve stem will not readily become injured or broken in its attachment to said flap.

These and other objects and advantages it 55 is believed will be comprehended by a perusal of the following description taken in connection with the drawings forming a

part of this specification, in which Figure 1 is a longitudinal section of my improved foot ball taken in line with the valve, the valve being in side elevation and the ball 60 distended, the valve being placed through the closing flap at a point where the casing is laced or sewed.

Fig. 2 is a plan view of Fig. 1 and shows the ball casing sewed together on both sides 65 of the valve opening where the bladder is introduced into the casing.

Fig. 3 is a broken cross section of a foot ball with the casing opened, and shows the bladder inserted and its valve thrust through 70 the closing flap preparatory to the closing and sewing of the opened flaps of the casing.

Fig. 4 is a detail view of the valve and a longitudinal section of the bladder and the casing, at the junction where the valve stem 75 is received through the closing flap.

Fig. 5 is a detail vertical cross section of the valve showing the seating rims forming a part thereof and between which the closing flap is received.

Fig. 6 is a sectional view showing the parts of the valve prior to their vulcanization.

Fig. 7 is a detail view partly in section of the valve tube.

Fig. 8 is a detail view of the flap.

In the drawings, like marks of reference refer to corresponding or equivalent parts through the different views, in which A represents an inflatable bladder; B, a casing 90 or container of leather or other suitable material; and C, an interiorly-extending valve vulcanized to the bladder.

The valve C in certain details of its construction has been the subject of separate 95 Letters Patent, Serial No. 1,538,163, under date of May 19, 1925. The present application involves certain details of construction whereby the valve will be especially applicable to foot balls used by professional 100 players, and wherein a casing of leather is used for the ball cover, and the valve and its attachment to both the ball and its casing will be thoroughly protected.

The casing B is formed of suitable materials in the usual manner for foot balls and is provided midway of its length with a slit 1 through which the bladder may be placed in the casing. Within the casing and sewed to it at one side of the slit, the 105 usual flap 2 is secured by a line of stitches 3. This flap, also of leather, vulcanized

2
fabric or other suitable material, extends beyond said slit to overlap the same, and it is formed with a hole 4, (see Fig. 8), having oppositely-disposed side slits 5, so that the lips made by slitting may be folded back and permit an end rim 6 of the valve C to be thrust through in the fitting of the valve to the casing.

In making up the tube of a valve C, a portion of said tube, including the neck 16 and that part of said tube above its bend, (as shown in Fig. 5), is of rubberized cord 7, with the strands running lengthwise. This cord is cut from a sheet of the material and wrapped about a forming core, after which another layer of gum rubber 9 is wound about said cord and extends below it in double ply to a point necessary for the completed tube. About this tube and slightly below its corded upper extremity, a flat ring 10 of gum rubber is placed, after which said tube is flared outwardly, as shown in Fig. 6, and three flat rings are placed upon said flaring portion, viz., a gum rubber ring 12, a middle ring 13 of fabric or rubberized cloth, and a ring 14 of gum rubber, preparatory to placing the assemblage of parts in a forming-up mould. The vulcanizing of the parts effects an amalgamation of the fabric disc 13 on the outspread ends of the cord top 7 of the tubular part, as shown in Fig. 5, and produces a tough and durable upper portion or neck for engaging the flap of a foot ball casing in such manner that said neck will not become disengaged nor broken in use.

When vulcanized, the parts 12, 13 and 14 form an end rim 6, the ring 10 forms a base 11, and the tubular part between the base 11 and rim 6, a neck 16 of a valve.

In placing a bladder A in a casing B, the rim 6 of the valve is bent upon itself and together with the neck 16 thrust through the slits 5 and the hole 4 of the flap 2, with the rim 6 lying between the casing B and said flap.

It is understood that the base 11, when a valve has been made up, is vulcanized on the exterior of a bladder with the curved end of the valve inside the bladder, as shown.

A bladder having been fitted with a valve, as set forth, and placed in a casing, the opening of the casing is closed over the bladder and the indrawn edges of said casing sewed or laced together, as expedient.

In Fig. 2 I have shown a foot ball with the edges of the casing sewed together, except a small space immediately over the valve opening. Should occasion arise, said casing at this point may be thrust apart sufficiently to permit an instrument to be thrust into the neck of the valve to deflate the bladder, or permit the nozzle of a pump to be inserted to inflate it.

From the foregoing description of my invention, taken in connection with the accompanying drawing, a more extended explanation of its objects and advantages will not be necessary.

Having, therefore, set forth my invention, what I claim as new and desire to secure by Letters Patent, is:

1. In an article of the class set forth, the combination with a casing having an opening capable of closure along contiguous edges, an inner closure flap attached to said casing adapted to cover said contiguous edges, an inflatable ball adapted to be received in said casing, said closure flap having a valve-stem hole with marginal slits, said ball having an internally-extending valve stem with an outer-extending neck portion having an end rim, said neck and rim adapted to pass through said valve-stem hole and marginal slits, with said end rim seating on said closure flap, and said casing adapted to be closed over said valve neck rim.

2. In an article of the class set forth, the combination with a casing having an opening capable of closure along contiguous edges, an inner closure flap adapted to close said contiguous edges, an inflatable ball adapted to be received in said casing, said closure flap having a valve-stem hole with oppositely-disposed marginal slits, said ball having an internally-extending valve stem with an outer formed neck portion having a base rim vulcanized to said ball and carrying at its outer end an integral rim, said neck and rim adapted to be thrust through said valve-stem hole and marginal slits, with said rim seating on said closure flap, and said casing adapted to be closed over said valve-neck.

3. In an article of the class set forth, the combination with a casing having an opening capable of closure along contiguous edges, an inner closing flap adapted to cover said contiguous edges and an inflatable ball adapted to be received within said casing, said closure flap having a valve-stem hole with oppositely-disposed marginal slits, said ball having an internally-extending valve stem with an outer formed neck portion, said valve stem being vulcanized to said ball and carrying at its outer end an integral rim adapted to be folded or bent upon itself and together with said neck portion to be thrust through said valve-stem hole and marginal slits, with said rim adapted to seat on said closure flap, and said casing adapted to be closed over said valve neck rim.

4. In an article of the class set forth, the combination of a casing having an opening capable of closure along contiguous edges, an inner closure flap adapted to cover said contiguous edges and formed with a

- valve-stem hole with oppositely-disposed marginal slits, and an inflatable ball adapted to be received in said casing, said ball having an internally-extending valve stem with
- 5 an outer neck portion formed with an outer end rim and having a base rim vulcanized to said ball, an upper portion of said valve stem including its neck comprising an inner ply of longitudinally-arranged cords and
- 10 an outer ply of rubber, the lower portion of said valve stem being a reinforced continuation of said outer ply rubber, said valve-stem neck and outer end rim adapted to pass through said valve-stem hole and marginal slits, with said rim seating on said closure flap, and said casing adapted to close over the rim of said valve-stem neck.
5. In an article of the class set forth, the combination with a casing having an opening capable of closure along contiguous edges, an inner closure flap adapted to cover said contiguous edges, said flap having a valve-stem hole with marginal slits, and an inflatable ball adapted to be received
- 20 through said opening, of a valve carried by said ball and having a tubular stem vulcanized to said ball with its valvular portion extending into said ball and formed with an exterior neck portion with an end rim adapted to be received through said valve hole and marginal slits, with said rim seating on said flap, said valve stem above

its valve portion and end rim being reinforced with material of a pliable, tough material, substantially as and for the purpose set forth. 35

6. In an article of the class set forth, a tubular valve stem having the inner wall of its intake end formed of longitudinally-disposed rubberized cord, the opposite end of 40 said tube, including an outer ply encompassing said intake end, being of rubber, said tube having an end rim formed at its intake end and a uniformly spaced flange below said rim, said rim and flange forming 45 a part of said valve stem, substantially as and for the purpose set forth.

7. In an article of the class set forth, a tubular valve stem having the inner wall of its intake opening formed from longitudinally-disposed rubberized cord with its upper end flared outwardly and forming a marginal rim, the opposite end of said tube, including an outer ply encompassing said intake end, being of gum rubber, an end 50 rim comprising an outer and under ply of gum rubber and a middle ply of fabric vulcanized to the flaring upper end of said valve stem and forming an end rim, and a 55 gum rubber rim equally spaced from said end rim vulcanized to said valve stem, substantially as and for the purpose set forth. 60
